UNITED STATES PATENT OFFICE.

CHARLES A. McCANN, OF NEW YORK, N. Y.

DESIGN FOR A PAPER-WEIGHT OR SIMILAR ARTICLE.

45,197.

Specification for Design.

Patented Feb. 3, 1914.

Application filed May 23, 1913. Serial No. 769,495. Term of patent 7 years.

To all whom it may concern:

Be it known that I, CHARLES A. McCANN, a citizen of the United States, residing at New York, in the county of New York and State of New York, have invented a new, original, and ornamental Design for a Paper-Weight or Similar Article, of which the following is a specification, reference being had to the accompanying drawings, forming part thereof.

Figure 1 is a front elevation of a paper-weight, or similar article, showing my new

design. Fig. 2 is a rear elevation of the same.

The base is substantially circular with a flat bottom; and the bell portion is a miniature representation of the Liberty Bell.

I claim:

The ornamental design for a paper-weight or similar article, as shown and described.

CHAS. A. McCANN.
